UNITED STATES PATENT OFFICE.

GEORGE B. COLEMAN, OF MEMPHIS, TENNESSEE.

SHOE-POLISHER.

SPECIFICATION forming part of Letters Patent No. 752,143, dated February 16, 1904.

Application filed March 3, 1903. Serial No. 145,910. (No model.)

To all whom it may concern:

Be it known that I, GEORGE B. COLEMAN, a citizen of the United States, residing at Memphis, Shelby county, State of Tennessee, have invented certain new and useful Improvements in Shoe-Polishers, of which the following is a specification.

The invention relates to improvements in shoe-polishers.

10 The object of the present invention is to provide for polishing patent-leather and enameled shoes a simple and efficient device adapted to carry a strip of cloth and capable of enabling the latter to be conveniently handled.

15 The invention consists in the construction and novel combination and arrangement of parts, as will be hereinafter fully described, and illustrated in the accompanying specification drawings, and pointed out in the claims 20 hereto appended.

In the drawings, Figure 1 is a perspective view of a shoe-polisher constructed in accordance with this invention. Fig. 2 is a longitudinal side elevation of the same. Fig. 3 is a 25 plan view of the device looking up from below. Fig. 4 is a mechanical perspective of the polishing-belt.

Like numerals of reference designate corresponding parts in all the figures of the drawings.

30 1 designates a back, preferably made of springy wood, of substantially equal breadth with the cloth to be used and having one end prolonged and shaped into a handle 2, by which it may be operated.

35 3 and 4 are detachable hooks having two prongs 5 curved to hook over and engage notches 6 in the outer end of the back 1 or holes 7 in the handle end and are broadened 40 out into loops 8 to hold the polishing-cloth 9. This cloth is formed as a continuous strip or belt, so that it may be shifted as it soils, or, if desired, the portion used for rough polishing may be used and the other section then 45 be shifted into position to complete the job.

If so desired, two strips of cloth of different textures, 11 and 12, may be joined together to form the belt, and these may then be shifted or use as desired. The strip 11 is preferably of coarse or rough cloth for initial pol-

ishing and the strip 12 of smooth cloth to give the finishing gloss to the shoe. The back is arched in order to give sufficient tension to the belt 9 to prevent the shoe being struck during use.

55 If desired to remove the polishing-belt, the hook 4 at the outer end is simply lifted off the handle. The opposite hook can then be removed and the belt be removed and turned wrong side out and again be put in use or renewed, as desired. The polishing-cloth is preferably a piece of canton-flannel or other soft material used in a single or double thickness.

The invention has the following advantages: 65

The device, which is simple and comparatively inexpensive in construction, is strong and durable and is adapted to enable a piece of fabric to be rapidly and conveniently passed over a shoe to polish the same.

70 The device, which can be conveniently constructed of a single flat strip of wood and the two hooks, enables the strip of fabric to be readily applied to and removed from it and to be shifted or turned, as desired, and entirely 75 obviates any difficulty from the cloth slipping or tearing.

Changes in the form, proportion, and minor details of construction may be resorted to without departing from the spirit or sacrificing 80 any of the advantages of this invention.

Having described the invention, what is claimed as new is—

1. In a shoe-polisher, the combination with 85 an arch spring-back having one end extended to form a handle, said back being notched at one end and having holes through the opposite end where the handle begins, of detachable hooks engaging said back and resting in said notches and holes, said hooks being extended below said back and formed into loops and a strip of polishing fabric carried by said loops.

2. In a shoe-polisher, the combination with 95 an arch spring-back having notches near its opposite ends, of similar hooks engaging said back at said notches, said hooks being extended below said back and formed into loops and a belt of polishing-cloth carried by said loops.

3. In a shoe-polishing device, the combination with an arch spring-back; oppositely-disposed hooks attached to said back, said hooks being extended below said back and formed into loops, of a polishing-belt stretched on said loops, said belt being made of two pieces of cloth of different texture.

4. A shoe-polishing device, comprising an arched back, oppositely-disposed hooks attached to and extending beneath said back and

a polishing-belt stretched on said hooks made of two pieces of cloth of different texture.

In testimony whereof I have signed my name to this specification in the presence of two subscribing witnesses.

GEORGE B. COLEMAN.
